UNITED STATES PATENT OFFICE.

EUGÈNE G. RESSENCOURT, OF ST. LOUIS, MISSOURI, ASSIGNOR TO ELIOT H. CHAMBERLAIN, TRUSTEE, OF ST. LOUIS, MISSOURI.

APPARATUS FOR MAKING FRUIT EXTRACTS.

1,017,800.

Specification of Letters Patent.

Patented Feb. 20, 1912.

Application filed October 26, 1910. Serial No. 589,130.

To all whom it may concern:

Be it known that I, EUGÈNE G. RESSENCOURT, a citizen of the United States, residing at the city of St. Louis, Missouri, have 5 invented a certain new and useful Apparatus for Making Fruit Extracts, of which the following is such a full, clear, and exact description as will enable any one skilled in the art to which it appertains to make and 10 use the same, reference being had to the accompanying drawings, forming part of this specification.

My invention relates to an apparatus for making fruit extracts and the object of my 15 invention is to provide an apparatus in which the condition of the material can be constantly inspected and in which the temperature of the material in the apparatus may be accurately regulated.

20 The accompanying drawing is a sectional view of one form of apparatus made in accordance with my invention.

1 represents a retort which may be of any suitable shape but is preferably approximately spherical as shown in the drawing. Contained within the retort 1 is a cylindrical strainer 2 provided with a flange 3 at its upper end. This flange 3 is clamped between the body of the retort 1 and the cover 30 4 of the retort. This cover 4 is held in position by means of swing bolts 5 pivoted at 6 to the body of the retort and connecting with lugs 7 on the cover 4. Leading from the cover 4 of the retort to a suitable condenser 8 is a pipe 9 by means of which the 35 products of distillation are carried over from the retort to the condenser. In order to lift the strainer 2 out of the retort 1 the said strainer is provided with handles 10.

40 In order to inspect the interior of the retort 1 I provide the walls of said retort at one side with a glazed side opening 11 and at another point in the wall, preferably diagrammatical opposite to the side opening 11 45 I insert in the walls a transparent tube 12 for receiving an incandescent light bulb or any other suitable source of light for illuminating the interior of the retort.

In order to take the temperature of the 50 contents of the retort I insert in the walls of the retort a tube 13 adapted to receive a thermometer. This tube 13 should be of some good conducting material such, for instance, as copper.

55 14 is a pipe leading from the bottom of

the retort 1, and 15 is a pipe leading from the retort near its upper end. These pipes 14 and 15 are connected by means of a glass tube 16 forming a water gage to indicate the height of the contents of the retort 1. The 60 flow of liquid through the pipes 14, 15 and 16 is controlled by means of a valve 17 and the pipe 14 is provided at its outer end with a pet cock 18 by means of which the contents of the retort 1 may be drawn off. In order 65 to insert liquid in the retort 1 without removing the cover 4 I provide the walls of the said retort with a threaded plug 19.

In order to heat the retort 1 I provide around its lower part a water jacket 20 70 adapted to be heated by means of a gas burner 21. This burner 21 is supported in a sleeve 22 the upper end of which is secured to the retort 1. The water jacket 20 has leading from it pipes 23 and 24 respectively, 75 which are connected by means of a glass tube 25 forming a water gage for the contents of the water jacket. The pipe 24 is also preferably provided with a pressure gage 26 to indicate the pressure of the 80 contents of the water jacket 20. The flow of liquid through the pipes 23, 24 and 25 is controlled by means of a valve 27 and the outer end of the pipe 23 is provided with a pet cock 28 for drawing off the contents of 85 the water jacket 20. In order to introduce water into the jacket 20 I provide a container 29 connected to the said water jacket 20 by means of a pipe 30 in which is a valve 31. 90

In making fruit extract in my apparatus the crushed fruit together with sugar or other necessary material is placed within the perforated strainer 2 so that the fruit pulp is kept out of contact with the walls of the 95 retort 1. Within the retort 1 is placed the necessary liquids for extracting the aroma from the fruit pulp. The retort 1 is heated by means of the burner 21 and as the water jacket 20 is interposed danger of overheating 100 the contents of the retort 1 is obviated. By means of the side opening 11 and illuminating tube 12 the contents of the retort 1 may be continually observed so that the distillation may be carried on the proper length of 105 time and at the proper rate.

Having fully described my invention, what I claim as new and desire to secure by Letters Patent of the United States is:

1. In an apparatus for making fruit ex- 110

tract, the combination with a retort, of a shell inclosing the lower part of said retort and forming a water jacket, a pipe leading from the lower part of said shell, a water 5 gage extending from said pipe to the upper part of said shell, a valved reservoir connected to the water jacket for supplying water thereto, a sleeve surrounding said water jacket and forming a support for the 10 retort, said sleeve also forming a combustion chamber, and a burner situated within said combustion chamber.

2. In an apparatus for making fruit extract, the combination with a retort, of a shell inclosing the lower part of said retort and forming a water jacket, a sleeve surrounding said water jacket, a pipe leading from the lower part of said shell through 15 said sleeve, a water gage connecting said pipe with the upper part of said shell, a second pipe leading from the lower part of said retort through said shell and said sleeve, a second water gage connecting said pipe with the other part of said retort, and 20 a valved reservoir connected with said jacket for supplying water thereto.

3. In an apparatus for making fruit extract, the combination with a retort having

a restricted mouth, of a substantially cylindrical foraminous container provided with 30 a flange adapted to rest on the lip of said mouth, a cover and means for clamping said cover against said flange, a pipe leading from said cover, and a condenser connected to said pipe.

4. In an apparatus for making fruit extract, the combination with a retort having a restricted mouth, of a substantially cylindrical foraminous container provided with 35 a flange adapted to rest on the lip of said mouth, a cover provided with lugs, swing bolts pivoted to said retort, nuts on said swing bolts adapted to engage with the lugs to clamp said cover against said flange, a pipe leading from said cover, a condenser 40 connected to said pipe, a shell inclosing the lower part of said retort and forming the water jacket, a sleeve surrounding said jacket, and a burner in said sleeve.

In testimony whereof, I have hereunto set 50 my hand and affixed my seal in the presence of the two subscribing witnesses.

EUGÈNE G. RESSENCOURT. [L. S.]
